Inventor

By his Attorney *Frank A. Kapp*

UNITED STATES PATENT OFFICE.

BYRON B. GOLDSMITH, OF NEW YORK, N. Y.

INK CARTRIDGE.

Original application filed March 2, 1922, Serial No. 540,488. Divided and this application filed February 16, 1923. Serial No. 619,346.

To all whom it may concern:

Be it known that I, BYRON B. GOLDSMITH, a citizen of the United States, residing in New York, county and State of New York, 5 have invented a certain Improvement in Ink Cartridges, of which the following is a specification.

The many inconveniences and disadvantages of transporting and storing ink in 10 liquid form are well recognized and various ways have been proposed for avoiding them by supplying apparatus whereby solid ink-producing material might be supplied to the consumer in such a way as to make it possible to produce a liquid ink by the mere addition of water when and where the ink was 15 needed.

Dry ink powders variously compounded, 20 and intended to be used by solution in water at, or near the time and place of use, are well known in the art; but they are awkward to use and uncertain in effect, particularly in the hands of the average unskilled consumer.

25 The present invention relates to a novel means for the preparation of ink powder of any kind in a manner insuring the making of ink of exactly such proportions as are deemed best in a given case, without waste 30 of powder and practically instantaneously. At the same time my improvement provides a very convenient package for shipping the ink powder ready for instant use, which package perfectly protects the powder and 35 keeps it in condition for insuring perfect results when used. The invention also has the advantage that it prevents accidental spilling on hands, clothing and so forth.

The principal or basic element of the 40 invention, which is claimed as novel per se, is a cartridge comprising a capsule, which may be given a variety of shapes, but is always characterized by the presence of a thin layer of ink powder (preferably uniformly distributed) which is confined between two 45 protective layers of a permeable nature, although not necessarily in contact with both layers. The protective layers or either of them should be made of a permeable material such as cloth or the like.

50 These capsules may be combined with a supporting guiding element to form cartridges or with appropriate vessels used as ink stands, and both of these combinations

form the subject matter of certain of the 55 claims herein.

This is a division of an application resulting in my U. S. Letters Patent No. 1,518,503 dated December 9th, 1924.

Certain embodiments of this invention are 60 illustrated by way of example in the accompanying drawings wherein Figures 1 and 1^a are views partly in section and partly in perspective showing two forms of a circular capsule, Figure 2 is a sectional view of a 65 simple form of cartridge with a removable capsule, Figure 3 is a sectional view of another form of cartridge provided with a number of capsules, Figure 4 is a view in section of a drum-shaped capsule, and Figure 5 is a view partly in elevation and partly 70 in section showing another mode of applying the invention to an inkstand.

In the simplest form of capsule a thin layer of ink powder 10 is spread uniformly 75 over a sheet or layer 11 of permeable material, preferably cloth or the like, and over this is placed a second similar layer 12, the whole being fastened together at the perimeter, as at 13.

80 As shown in Figure 1^a, there may be a central permeable layer 14, having thin layers of ink powder 15 and 16 on its opposite faces, confined in place by outer permeable layers 17 and 18.

85 In use, water is simply poured through a capsule of this kind and ink is produced. No shaking or stirring is required and none of the powder can get loose to stain the fingers, clothing etc.

90 In Figure 2 is shown a simple form of cartridge for putting to use the simple capsule of Figure 1 or 1^a. This comprises a support and pouring tube 19, to one end of which the capsule can be applied so as to 95 entirely close the opening, as shown at 20. The capsule may be applied to the tube 19 in any manner, as, for instance, by means of the threaded collar 21.

100 Where a larger quantity of ink or a more intense ink is to be made at once, a number of capsules 22 can be inserted at intervals in the main tube 19, being held apart in parallel relation by short interior friction sleeves 23, or otherwise.

105 In Figure 5, the inkstand 30 has a threaded filling orifice at 31 over which the capsule 20 is laid, being held in place by the

removable funnel 32, screwed on over the orifice 31. Water poured into the funnel will percolate through the capsule into the inkstand and be converted into ink on the way.

As shown in Figure 4, the permeable sides of the capsule need not necessarily both be in contact with the powder. Here the sides 33 and 34 are held apart by a rim 35, so as to 10 form a small drum-shaped capsule, partly empty and partly filled with the powder 36.

Although I have used the term "ink powder", I desire to be understood as also covering, by this expression, particles of a 15 larger size than actual powder; as in some cases there is an advantage in using such larger sizes with percolating spaces between them.

The examples described above are sufficient to make it clear that many changes 20 may be made in the form and arrangement of the devices described without departing from the scope of the invention which is not limited to the details herein described and 25 shown.

What is claimed is—

1. An ink cartridge comprising a pouring tube in combination with a capsule closing the same comprising two or more layers of permeable material enclosing a layer of ink 30 powder.

2. An ink cartridge as in claim 1 wherein one at least of the permeable layers is composed of absorbent material.

3. An ink cartridge as in claim 1 wherein 35 a plurality of ink capsules are held within the pouring tube.

4. An ink cartridge as in claim 1 wherein a plurality of ink capsules are held within the pouring tube by means of spacing sleeves 40 fitting frictionally within the tube.

5. Apparatus for making liquid ink comprising a cylindrical pouring tube of substantially uniform bore, in combination with a capsule containing ink powder and extending completely across and within the end of said tube. 45

In testimony whereof I have hereto set my hand on this 14 day of February, 1923.

BYRON B. GOLDSMITH.
